APPARATUS FOR CASTING CURVED STEREO-TYPED PLATES WITH TENSION LOCKUP POCKETS THEREIN

Charles L. Ricards, South Plainfield, and John A. Isbell, Plainfield, N. J., assignors to Wood News-paper Machinery Corporation, Plainfield, N. J., a corporation of Virginia

Application December 27, 1945, Serial No. 637,336

4 Claims. (Cl. 22—2)

1

This invention relates to a method of and apparatus for casting stereotype plates and more particularly to a method of and machine for casting a stereotype plate having pockets on its inner face for the reception of tension clamps.

In the use of stereotype plates with modern high speed presses, where centrifugal force must be taken into account, the use of the conventional end clamp lock-up mechanisms to secure the plate to the printing cylinder has not proved satisfactory and it has been proposed to provide specially designed plate clamping fingers which are incorporated in the printing cylinders and which securely hold the stereotype plates in position on the cylinders under circumferential tension rather than under compression. The use of this tension lock-up mechanism has presented new problems in the manufacture of stereotype plates. If the plates are manufactured as heretofore, it is necessary to form pockets on their inner surfaces by a milling operation, or in some other suitable manner, thus necessitating a separate operation or requiring the milling operation to be performed in conjunction with some subsequent finishing step as, for instance, the shaving of the plate.

In accordance with the present invention, we provide a method wherein pockets are formed in the plate casting operation by retractable cores which are withdrawn from the pockets into the plate casting cylinder or core after the plate has been cast to permit the plate to be readily stripped from the cylinder.

The invention further comprises suitable apparatus consisting of the usual casting box and plate cylinder in which the plate cylinder is provided with a number of retractable pocket forming cores equal to the number of pockets desired in the stereotype plate, together with suitable means for projecting the cores when the plate cylinder is moved into casting position and permitting the cores to be retracted when the plate cylinder is moved from the casting box to permit the plate to be stripped from the cylinder.

Other objects and advantages of the invention will be apparent from the following description taken in conjunction with the accompanying drawings, in which:

Fig. 1 is a vertical, sectional view of an automatic plate casting apparatus embodying the invention;

Fig. 2 is a horizontal, sectional view on line 2—2 of Fig. 1 showing one pair of pocket forming core members in projected position on the side of the cylinder within the casting box and show-

2

ing another pair of pocket forming core members in retracted position with the stereotype plate being stripped from the cylinder;

Fig. 3 is an enlarged view through a pair of pocket forming core members and their associated parts in substantially the plane of Fig. 2;

Fig. 4 is a sectional view at right angles to Figs. 2 and 3 on the line 4—4 of Fig. 2;

Fig. 5 is a plan view of the parts shown in Fig. 4;

Fig. 6 is a vertical, sectional view of a plate casting machine illustrating another means for projecting and retracting the pocket forming core members, the view being taken on line 6—6 of Fig. 7;

Fig. 7 is a horizontal, sectional view on the line 7—7 of Fig. 6;

Fig. 8 is a plan view taken on the line 8—8 of Fig. 6;

Fig. 9 is a horizontal sectional view on the line 9—9 of Fig. 6;

Fig. 10 is a side elevation of a set of pocket forming core members and the actuating mechanism therefor;

Fig. 11 is a side elevation of a stereotype plate showing the pockets formed therein;

Fig. 12 is a horizontal sectional view showing one form of the invention applied to a universal plate casting machine;

Fig. 13 is a vertical, sectional view on line 13—13 of Fig. 12;

Fig. 14 is a horizontal sectional view illustrating another form of the invention applied to another type of plate casting machine;

Fig. 15 is a vertical sectional view on line 15—15 of Fig. 14; and

Fig. 16 is a side elevation of the form of the invention shown in Figs. 14 and 15.

In the form illustrated in Figs. 1 to 5 of the drawings, the invention is shown applied to an automatic plate casting machine comprising a substantially semi-cylindrical casting box 2 in which is mounted a plate cylinder or core 4. The plate cylinder is rotatable about its axis and one-half of the cylinder within the casting box cooperates with the casting box to form a mold cavity 14 for the casting of a stereotype plate while a previously cast stereotype plate is being stripped from the other half of the cylinder. The retraction of the pocket forming cores on one-half of the cylinder is accomplished by the lateral movement of the plate being stripped from the cylinder, and the pocket cores on the other half of the cylinder are projected into operative position by means of torsion springs and by inter-

connection between the pocket cores on one half of the cylinder and those on the other half of the cylinder.

The machine is mounted on a suitable base 6 by means of a pedestal 8. The plate cylinder is supported on a stationary axle 10, through suitable upper and lower journals 12. A matrix (not shown) is secured to the inner surface of the casting box and the metal for forming the stereotype plate is poured into the mold through the opening 16. The upper end of the cylinder is closed by an end plate 18. A gear or pinion 20 is mounted on the axle 10 to rotate with respect thereto and is capable of being connected to the end plate 18 of the cylinder by suitable clutch mechanism 22 to rotate the cylinder a half revolution after a plate has been cast. Cooling of the cast plate is accomplished by delivering water or other cooling fluid through a conduit 24 in the base to the interior of the cylinder. This cooling fluid passes through openings in a sleeve 26 surrounding the stationary shaft 10 and exhausts through openings 27 in the lower end wall of the cylinder. The casting box may also be provided with a cooling space 28 having inlets and outlets 30 connected thereto. The parts heretofore described are of conventional construction in automatic stereotype plate casting machines and form no part of the invention, except in the combination claimed.

In Fig. 11 of the drawings we have illustrated a stereotype plate P having a plurality of pockets 32 cast in its inner face adjacent the end edges of the plate. In the form of the invention illustrated in Figs. 1 to 5 of the drawings, these pockets are formed by segmental pocket core members 34 which are preferably arranged in pairs as shown in Figs. 2 and 3 and are fixed in openings in the plate cylinder. The ends 35 of the core members are properly shaped to form pockets 32 of a desired contour to receive the tension clamps. The pocket core mechanism is mounted in a suitable holder 36 shaped to fit the opening in the plate cylinder and secured thereto by means of clamps 38 and bolts 40 (see Figs. 3 and 5). The segmental pocket core members 34 are mounted in arcuate passages 42 in the holders and are adapted to be projected when the half of the cylinder in which the pocket core member is mounted is within the casting box and retracted when the cast plate is being stripped from the cylinder (see Figs. 2 and 3). The holder 36 is formed of two parts 44 and 46 secured to each other by bolts 48. The holders are provided with slots 50 through which levers 52 extend (Fig. 4). The end of each of the levers 52 is received in an opening 54 in a core pocket member 34. The levers 52 are mounted on studs 56 and surrounded by coil springs 58 mounted in the holders. One end of each coil spring is attached to the lever as at 60 and the other end 62 is attached to a cap 64. Thus, the pressure of the spring can be varied by rotating the cap 64. When the desired pressure is obtained, a screw 66, which passes through an opening in the cap, is fixed in one of several openings in the holder to lock the spring which then exerts the desired pressure on the lever 52 to project the pocket core member 34. The springs are adjusted to retain the lever 52 against a stop 68 (see Fig. 3) and project the core member 34 the exact amount desired to form a pocket of the desired size in the cast plate.

Beyond the stud 56, each of the levers 52 is provided with a segment 70 of gear teeth. The segments 70 of a pair of pocket core members 34

mesh with racks 72 and 74 formed on plungers 76 and 78 (see Fig. 3) and these plungers are mounted in a suitable bore 80 in the holder. One of the plungers is counter-bored as at 82 to receive a spring 84 and a poppet 86, the head of which abuts but is not attached to the end of the other plunger 78. A stop collar 88 is arranged on the outer end of plunger 78 within the bore to limit the movement of the poppet 86. The holder is provided with a drain hole 90 to carry off any seepage of cooling water entering the unit (Fig. 4). A spring clip 92 (see Fig. 3) is arranged around the meeting ends of the plungers 76 and 78 to guard against seepage of water.

In Fig. 1, a plate P, which has been cast, is shown at the time of being stripped from the half of the cylinder remote from the casting box. As shown, the edges of the plate have been engaged by plate fingers 94 (Fig. 2). The other half of the cylinder is in position in the casting box, forming the mold cavity 14 for the reception of molten type metal to produce another stereotype plate. As the plate P is stripped by the plate fingers 94, it pushes the core members 34 out of its path to a point where they clear the plate and permit the springs 58 to return the core members back to casting position. On the half of the plate cylinder within the casting box, the core members 34 are projected by the springs 58, and the plate when cast will have the pockets 32 formed therein by the core members. The springs 58 bias the core members 34 toward their extended positions so that in normal operation, the core members 34 on the half of the plate cylinder within the casting box are extended by these springs. Should one of these members 34 stick in its retracted position when it is pushed inward by the stripping of a casting plate therefrom, and remain in such position when brought within the casting box in preparation for the next casting operation, then the retraction of the opposite set of core members 34 by the stripping of a plate therefrom will dislodge and extend the stuck fingers. When the outer core members 34 are retracted by the stripping of a plate, as shown at the right side of Fig. 3, the plunger 78 is positively moved to the left, moving the poppet 86 to the left and thus compressing the spring 84 thereby biasing the plunger 76 to the left. The force of the compressed spring 84 is thus applied through the rack 72 and the segment 70 of gear teeth to assist the springs 58 in projecting the core member 34 on the left of Fig. 3 to its extended pocket forming position.

In Figs. 6 to 10 of the drawings, another form of the invention is shown applied to an automatic casting machine of the type shown in Figs. 1 to 5, and the conventional parts of the casting machine are designated by the same reference numerals. In this form of the invention, the core members which are employed to form the plate pockets 32 are positively withdrawn and protruded by the rotation of the cylinder. The cylinder 4 is provided with a detachable head 100 to facilitate manufacture and assembly of the mechanism for inserting and retracting the pocket forming cores. This head is secured to the cylinder by bolts 102. As in the form of the invention heretofore described, the pocket core members are mounted in holders 104 secured in suitable openings in the wall of the cylinder by clamps 106 (see Fig. 6). The cores 108 are slidably mounted in openings 110 in the holders 104 and the end portions 112 of the cores are suit-

ably shaped to form pockets of the desired contour. The inner ends 114 of the core members are cylindrical and are mounted in guides 116 secured to the holders 104. Packing glands 118 surround the cylindrical portions of the core members to prevent seepage of cooling water.

A detailed view of a number of the core members and the operating mechanism therefor is shown in Fig. 10. As shown, a plurality of the core members 108, adapted to form a series of pockets adjacent an edge of a plate P, are connected together by tie bars 120. Connecting links 122 are pivotally connected to the tie bars by pins 124 and these links are secured to cams fixed to a shaft 126, two of such shafts extending vertically of the machine at positions 180° from each other as shown in Fig. 7.

The shafts 126 are rotated by rotation of the cylinder 4 through a planetary gear train shown in Figs. 6, 8 and 9. A stationary gear 128 is secured to the shaft or axle 10 and this gear drives intermediate gears 130 mounted on stub shafts in the detachable cover plate 100. The stub shafts carry pinions 132 which in turn mesh with gears or pinions 134 mounted on the shafts 126.

When the cylinder is rotated, gears 130 rotate around the stationary sun gear 128 and through the pinions 132 impart rotary motion to the pinions 134 on the shafts 126. The ratio of the gearing is such that when the cylinder makes one revolution, the shafts 126 also make one revolution. Thus, the half revolution made by the cylinder to move a cast plate from the casting box 2, as shown at the left in Fig. 7 of the drawings, to the position for stripping the plate, as shown to the right in Fig. 7 of the drawings, causes each of the cam shafts 126 to make a half revolution. Through connecting links 122, the core members 108 on the left side of the cylinder are protruded out into the mold cavity ready for the next casting operation whereas the core members on the other half of the cylinder are retracted as shown to permit the cast plate to be removed from the cylinder by the plate fingers 94.

The cam shafts 126 may be supported by intermediate bearings 136 which are inserted in the cylinder wall and held in place by clamps similar to the clamps 106. By providing these bearings as separate members and not as part of the cylinder construction, machining of the inside surface of the cylinder to insure a uniform wall thickness is facilitated.

In Figs. 12 and 13 the invention is shown applied to a stereotype casting machine of a different type. In this type of machine we provide a casting box 138 which is substantially semi-cylindrical in horizontal cross-section as shown in Fig. 12 of the drawings, and this casting box cooperates with a semi-cylindrical core 140. The core, when in closed position, is arranged slightly spaced from the casting box to provide a mold cavity 142 between them, and when the cast plate is to be removed, the core is tilted to the dotted line position shown in Fig. 13 of the drawings. The casting box is supported by side frames 144 and the core is movably supported by rollers 146 on tracks 148 carried by the side frames. The rollers 146 are journaled on studs 147 carried by brackets 150 mounted on the core. The lower ends of these brackets are pivotally connected to links 152 and the opposite ends of the links 153 are pivotally mounted on studs 154 carried by the frame 156 of the machine. This method of supporting the core to permit it to assume either

the vertical position shown in Fig. 12 for casting or to assume the substantially horizontal position shown in dotted lines in Fig. 13 to permit ejecting of the cast plate is well known in the art and forms no part of the present invention except in the combination claimed.

In the form of the invention illustrated in Figs. 12 and 13, we provide holders 158 for the pocket core members, these holders being inserted in suitable openings in the core and retained in position by clamps 160 and bolts 162. The holders are provided with arcuate slots 164, similar to the construction described in connection with the form of the invention shown in Figs. 1 to 5, and receive pocket core members 166 which are adapted to be inserted in the mold cavity as shown in Fig. 12 to form the pockets 32 when the plate is cast, and to be retracted to permit stripping of the cast plate. The pocket core members are projected by levers 168 which are received in slots or openings in the receivers and these levers are mounted on studs 170 and provided with torsion springs similar to the springs 58 heretofore described to normally extend the pocket core members to operative position. Outward movement of each core member is limited by engagement between a portion of the lever 168 and a stop 172 formed on the holder 158. A push pin 174 engages a projection 176 on the lever 168, the lever being shaped as to be engaged by the push pin to assist the action of the torsion spring and insure that the lever is moved to the point where it engages the stop 172 and properly extends the pocket core member into the mold cavity. In this construction the core 140 is provided with an inner wall 178 to provide a water jacket 180 and as it is necessary to extend the opening over the holder 158 through this inner wall, it must be made water-tight. A packing gland 182 surrounds the push pin 174 and is provided with a flange 184 which is secured to the inner wall by means of bolts 186. Adjustable nut 187 is arranged within this gland and confines a packing 188 around the tubular push pin guide 190 which projects from the holder 158.

Motion of the push pins 174 is derived from the tilting of the core 140 from the vertical position shown in Fig. 13 of the drawings to the dotted line position. As the core is tilted, the angular relationship between the core and link 152 changes. A shaft 192 is journaled within the core and this shaft is provided with a bevel gear 194 on its lower end. Bevel gear 194 meshes with a bevel gear 196 mounted on a shaft 198 carried by and fixed to the links 152. When the core is swung to the dotted line position and the angular relationship between it and the links 152 is thus changed, shaft 198 and bevel gear 196 rotate shaft 192. Shaft 192 is provided with a plurality of cams 200 having high points 202 which engage push pins 174 when the core is swung to a vertical position to assist the torsion springs in moving the pocket core members 166 to operative position. The pocket core members 166 are withdrawn from the pockets when the core is in the dotted line position shown in Fig. 13 by the action of lifting the plate from the core. Positive withdrawal of the pocket core members 166 could be obtained by providing linkages between the shaft 192 and the push pins 174, if desired.

Figs. 14 to 16 illustrate the same general type of machine as that shown in Figs. 12 and 13 provided with other means for inserting and withdrawing the pocket core members. Parts of the apparatus which are identical to the parts illus-

trated in Figs. 12 and 13 are identified by the same reference numerals. In Fig. 14 of the drawings we have also illustrated the conventional slidable locking bars 204 by means of which the core is securely locked to the casting box 138 when the parts are in position for casting. A matrix 206 is also illustrated in this form of the invention and is engaged between the locking bars 204 and the packing strips 208. In this form of mechanism, the matrix moves out of the casting box 138 with the cast plate and is stripped therefrom by hand. The locking bars are moved laterally by means of a hand lever 210 which is pivoted to a stud 211 carried by one of the locking bars and simultaneous movement of the other locking bars is provided by toggle links 212 and a vertical sliding bar 214. These parts are of conventional construction and are not claimed except in combination with the parts shown herein.

Movement of the vertical sliding bar 214 is utilized to actuate the pocket core members in the form of the invention shown in Figs. 14, 15 and 16. The pocket core members 216 are mounted in suitable channels in the core and the inner ends of the core members are provided with racks 218. These racks engage gear segments 220 mounted on shafts 222 and 224 at the opposite sides of the machine. The shafts are geared in synchronism by bevel gears 226 and 228. These gears are carried by a stub shaft 230 mounted in bearings formed in brackets 232 on the inner side of the core. The stub shaft 230 is rotated by movement of the vertical sliding bar 214, the shaft being provided with a crank or lever 234 which is connected to the sliding bar by extending into an opening therein, as shown in Figs. 14 and 15.

The operation of this form of the invention will be apparent from the foregoing description. When the core 140 is moved to the vertical position adjacent the casting box for a casting operation and the lever 210 is moved upwardly from the dotted line position shown in Fig. 15 of the drawings for the purpose of locking the core to the casting box, movement of sliding bar 214 oscillates the shaft 230 which through bevel gears 226 and 228 oscillates shafts 222 and 224. Gear segments 220 carried by these shafts engage racks 218 on the core members 216 to move the core members outwardly and thus insert them in the mold cavity to form pockets of the desired size and shape when the stereotype plate is cast.

In the use of each of the described forms of apparatus, the molten type metal is poured into the cavity formed between the casting box and the core while the pocket core members protrude from the core surface. Thereafter, the cast plate is cooled, the plate is removed from the casting box with the core and is stripped from the core, the pocket core members being retracted to permit the stripping of the plate.

We claim:

1. In apparatus for casting curved stereotype plates including a concave semi-cylindrical casting box and a cylindrical core adapted to form an arcuate mold cavity therebetween, a stationary central shaft supporting said core for rotation to move semi-cylindrical plates cast on the core surface out of said casting box, the combination therewith of at least two pocket core members respectively carried by said core adjacent opposite sides of said mold cavity and movable from positions in which they extend outwardly into said mold cavity to retracted positions within said cylindrical core, a rotary shaft journalled within and extending lengthwise of

5 said core, gearing connected between said rotary shaft and said stationary central shaft and operated by rotation of said core for turning said rotary shaft, eccentrics on said rotary shaft and links connecting said eccentrics to said pocket core members whereby turning of said core moves said pocket core members.

2. In apparatus for casting curved stereotype plates including a concave semi-cylindrical casting box and a cylindrical core adapted to form an arcuate mold cavity therebetween and a stationary central shaft supporting said core for rotation to move semi-cylindrical plates cast on its surface out of said casting box, the combination therewith of at least two elongated pocket core members respectively carried by said core adjacent opposite sides of said mold cavity and movable lengthwise from positions in which they extend outwardly into said mold cavity to retracted positions within said cylindrical core, a rotary shaft journalled within said core, gearing connecting said rotary shaft and said stationary central shaft for rotating said rotary shaft when said core rotates, and links connected between said rotary shaft and said pocket core members for moving said pocket core members between their extended and retracted positions upon rotation of said core.

3. In apparatus for casting curved stereotype plates including a concave substantially semi-cylindrical casting box and a convex cylindrical core adapted to form an arcuate semi-cylindrical mold cavity therebetween, and a stationary central shaft supporting said core for rotation to present successive semi-cylindrical portions thereof adjacent said casting box, the combination therewith of two sets of elongated pocket core members carried by said cylindrical core, the members of each set being respectively disposed adjacent opposite sides of said mold cavity on opposite semi-cylindrical portions of said core, all of said pocket core members being movable lengthwise through openings in the cylindrical core surface between retracted positions beneath such surface and extended positions in which their ends extend into the mold cavity, two rotary shafts within said core, gearing operatively connecting said rotary shafts to said stationary central shaft for rotating said rotary shafts when said core rotates, eccentrics on said rotary shafts and links connected between said eccentrics and said respective sets of pocket core members for moving said core members between their extended and retracted positions upon rotation of said cylindrical core.

4. In apparatus for casting curved stereotype plates including a concave substantially semi-cylindrical casting box and a convex cylindrical core adapted to form an arcuate semi-cylindrical mold cavity therebetween and a stationary central shaft supporting said core for rotation to present successive semi-cylindrical portions thereof adjacent said casting box, the combination therewith of two sets of elongated pocket core members carried by said cylindrical core, the members of each set being respectively disposed adjacent opposite sides of said mold cavity on opposite semi-cylindrical portions of said core, all of said pocket core members being movable lengthwise through openings in the cylindrical core surface between retracted positions in which their ends are beneath such surface and extended positions in which their ends extend into the mold cavity, two rotary shafts extending longitudinally of said core, each of said rotary shafts

lying substantially between the pocket core members of one of said sets, gearing connecting said rotary shafts to said stationary central shaft for turning said rotary shafts relative to said core as said core rotates, eccentric surfaces on 5 said rotary shafts and links connecting the pocket core members of each of said sets to the eccentric surface of the rotary shaft lying between said pocket core members whereby rotation of said rotary shafts moves said pocket core members between their extended and retracted positions.
